ONE-WIRE PRINTING-TELEGRAPH SYSTEM.

Application filed October 26, 1926. Serial No. 144,830.

This invention relates to printing telegraph systems of the class in which a single transmission circuit between the transmitter and the receiver (or receivers) controls all the operations of the latter, including setting of the type wheel or type-carrier, making the imprint, and effecting spacing between imprints. In systems of this class the type or printing characters are arranged in two rows on the type wheel, which is rotated step by step under the control of the usual electromagnetic escapement to bring the desired characters to the printing position, but in order to print from either row at will one or both elements of the printing couple must be "shifted". To make the "shift" it is necessary to rotate the type wheel to a "shift position" and make what is virtually an idle stroke of the printing elements. For example, suppose the letters of the alphabet are in one row in the type wheel and the numerals, fractions, and punctuation marks in the other, and that it is desired to print the letter G, followed by a number, say 5, then another letter. In this operation the type wheel is rotated step by step until G is at the impression point. The letter is then printed, after which the type wheel is rotated to the shift position. An idle stroke is then made (or a period is printed if the type has a period at the shift position), which by proper cooperation with the printing platen shifts the latter to the other or numeral row of type. The wheel is now rotated to bring "5" to the printing position, and the imprint is made, then in order to shift back to the letters row the type wheel must be again rotated to the shift position and another idle stroke.

Upon reflection it will be seen that rotating the type wheel to the shift position and making an idle stroke requires a certain amount of time, and that this time is lost since no useful letter or numeral is printed in the shifting operation. In using the system to report sales on stock exchanges or other exchanges the loss of time is sometimes very serious, as when the "market" is active. On such occasions the "ticker" may lag a half hour, or even more, whereas at such times it is particularly desirable to have all sales reported promptly since prices change most rapidly in an active market.

We have accordingly been led to devise our present invention, which has for its chief to provide a single circuit or "one wire" system

in which the shift from one row of type to another can be effected at any position of the type wheel, thereby effecting a marked increase in speed of operation. In fact, with the preferred embodiment hereinafter described we have been able to increase the speed as much as forty per cent, depending somewhat, of course, upon the skill of the sending operator. Another object is to provide for the purpose stated instrumentalities which can be added to or incorporated in existing systems at reasonable expense. A further object is to provide shift mechanism and shift controlling mechanism which is not limited to use in one-wire systems. To these and other ends the invention comprises the novel features and combinations hereinafter described.

In carrying out our invention in the preferred manner we make use of a principle which has been employed for other purposes in printing telegraphs, namely, variation in the strength of the current used to control or actuate the receiver, but so far as we are aware this principle has not heretofore been employed to effect the shift in a one-wire tape-printer or "ticker" system. By such means, we are able to do with a single transmission circuit what has hitherto required at least two in such systems, and we thus obtain the desired increase of speed without going to the large expense of a second "wire".

Of the various forms in which the invention can be embodied we have selected for specific illustration and description herein the one which at the present time we consider the most effective. This form is based on a widely used system in which the current sent over the transmission circuit is of alternating polarity, causing corresponding alternations in the polarity of the electromagnets which control the type wheel escapement of the receiver thereby causing or permitting the type wheel to rotate step by step. When the desired character has thus been brought to the impression point the final current impulse is prolonged, enabling such impulse to energize a magnet of longer time-constant, known generally as the printing or "press" magnet. The latter, thus energized, actuates the platen and spaces the "tape" along one step. In accordance with our invention as applied in the preferred manner to the system referred to, weak current causes imprints to be made from one row of type, say the row contain-

ing letters, and strong current causes imprints to be made from the other row. For this purpose the receiver is equipped with shift mechanism for producing relative shifting movement of the type wheel and printing platen, including an actuating electromagnet controlled by a relay which when weak current is sent through it has a field of insufficient strength to overcome the tension of the spring 10 which tends to swing the armature of the relay to its outer position. On the other hand, strong current produces a field strong enough to actuate the armature. In order to vary or change the current strength the keys on 15 the transmitting keyboard are arranged in two groups, corresponding to the two rows of type on the receiver type wheel, those in one group being connected directly to the current-supply mains and those in the other group 20 being connected to the mains through a relay magnet which, when energized, cuts a suitable resistance out of the transmission circuit and thereby increases the strength of the current transmitted.

25 Referring now to the accompanying drawings, in which the embodiment outlined above is illustrated,

Fig. 1 is a side view of the receiver or ticker, with portions of the enclosing casing 30 broken away to show the parts which are more directly involved in our invention. The receiver is of the type described in detail in the prior patents of George S. Hiltz, No. 1,085,124, issued January 27, 1914, and No. 35 1,558,610, issued Oct. 27, 1925, to which reference may be made for a complete description.

Fig. 2 is a detail front view of the shift mechanism, showing the shift magnet, the type wheel with its two rows of characters, 40 and the pivoted forked platen. In this view the platen is shown in position to print from the row containing numerals.

Fig. 3 is a detail front view of the platen and type wheel, the former being in position to print letters.

Fig. 4 is a detail side view from the right of Fig. 2, but omitting the type wheel.

Fig. 5 is a diagram of the wiring of the system, showing also, diagrammatically, the 50 keyboard, the transmitting "sunflower", and the transmitting commutator. Only one receiver is shown in this figure, but it will be understood that two or more, preferably in series with each other, can be controlled by the same transmitter.

Fig. 6 is a wiring diagram of a simpler form of the invention than that shown in Fig. 5.

Fig. 7 is a detail view illustrating another 60 embodiment of the invention.

The two-part type wheel 10-11 of the receiver or "ticker" shown in Figs. 1, 2 and 3 is mounted on a shaft 12 which is rotated step by step under the control of the con-

ventional escapement which is itself controlled or actuated by magnets 13, Fig. 5. The platen 14 is pivoted on the end 15 of an arm (not shown) connected with the armature (not shown) of the press magnet 16 so that when the magnet is energized the platen 70 will be thrown up, carrying the tape 17 up against the type wheel. The platen forked, as indicated, the type row from which the imprint is made depends upon the position of the platen. If in the position shown in 75 Fig. 2, the print will be made from row 11, whereas in the other position, Fig. 3, a character in row 10 will print. For the purpose of rocking the platen to either position at will it is provided with a tail 18 having a 80 cam slot 19 engaged by a finger 20 on the lower end of a lever 21 pivoted on the arm 15 and provided at its top with two oppositely extending fingers 22, 23. Overhanging these fingers is the rearwardly bent upper end of 85 a shift-arm 24 having a laterally and downwardly extending dog 25, and in rear of the dog 25 a similar dog 26 extending laterally in the opposite direction. If with the platen in the position of Fig. 2 the shift-arm 24 be 90 swung rearwardly (away from the observer) so that dog 25 overhangs finger 23, the upswing of the platen to make an imprint will first bring finger 23 up against the dog, and since the latter cannot move upwardly the 95 continued movement of the platen will cause depression of finger 23 by the dog, thereby rocking lever 21 clockwise, which in turn rocks the platen in the same direction to the position shown in Fig. 3. Continuing its 100 upward course, the right-hand arm of the platen brings the tape (not shown in Fig. 3) against a character in type row 10. If now the shift arm be swung forwardly to the position shown in Fig. 4, dog 26 will overhand finger 22 (not shown in Fig. 4) and at the next upswing of the platen the latter will be rocked back to the position shown in Fig. 2. Type row 11 will then print.

For rocking the shift-arm 24 it is fixed on 110 a rock-shaft 30 to which is also fixed the armature 31 of the shift magnet 32. A spring 33, connected to an arm 34 fixed on the rock-shaft urges the shaft and shift-arm rearwardly (or clockwise as seen in Fig. 4) so 115 that when the shift magnet is not energized, or is energized by weak current, the shift-arm will stand in its rearward position with dog 25 over finger 23, as will be readily understood. A stop 35 in the path of the arm 120 34 determines the rearward position of the shift-arm, and engagement of the armature 31 with the projecting cores of the shift magnet determines the forward position.

The escapement magnets, press magnet 125 and shift magnet may all be in the transmission line, in series with each other, as described hereinbefore, but it is preferable in

most cases to operate the press and shift magnets on local circuits under the control of relays in the transmission line.

Referring now to Fig. 5, 40 represents the transmitting keyboard, having two concentric annular busses 41, 42, each provided with spring-raised contacts or keys of which two on each are shown at 43, 44, 45, 46, to cooperate with underlying spring contacts, as 47, 48, 49, 50, which are connected in series with the respective segments (51, 52) of the sunflower 53, which latter is of the well known type, having a rotating wiper or contact 54 provided with a hub or slip ring 55 on which 15 bears a brush 56 connected through a clutch relay magnet 57 to ground G. Keyboard bus 41 is connected through a relay magnet 58 to the positive current-supply main 59, while bus 42 is connected to the same main through 20 current-control relay 60 (which controls the strength of the current over the transmission line, as hereafter explained) and line relay 61. The wiper 54 is rotated at appropriate speed by means of suitable gearing 25 (not shown) from the shaft 62, which also carries a commutator comprising a slip ring 63 engaged by a brush 64 connected to ground G', and a slip ring 65 cooperating with brushes 66, 67, and having an insulating segment 68. The shaft 62 can be arrested, with the commutator and wiper in any position by an electromagnetic clutch 69 controlled by the relay 57. The commutator and clutch mechanism are of a well known type, described in the prior patent of John Burry, 30 No. 540,420, issued June 4, 1895, and hence need not be described in detail here. Suffice it to say that shaft 62 is driven by a constantly running motor through the medium 35 of a friction clutch, so that the shaft and parts driven thereby can be arrested (by the clutch 69) at any time without stopping the motor.

Still referring to Fig. 5, the alternating current impulses by which the ticker escapement is actuated are sent over the line circuit by a relay comprising magnets 70, 71, whose armature, represented by contact 72, plays between fixed contacts 73, 74, and upon tracing the connections it will be seen that when the armature engages contact 73 the former is electrically connected to the positive main 59 by wire 75, and that when the armature is on contact 74 it (the armature) is connected to the negative main 76 by wire 77. The relay magnets 70, 71 are connected to commutator brushes 66, 67, respectively, and are connected by a common lead 78 to the positive main 59. With the commutator in 60 the position shown, current flows from main 59 through wire 78 to magnets 70, 71, but cannot go through 70 since the brush 66 is on the insulating segment 68. Hence the current flows through magnet 71, wire 79, brush 67, slip rings 65, 63, and brush 64 to ground 65

G''. This energizes magnet 71, the armature 72 of the pole-changing or transmitting relay is drawn over to contact 73, and a positive impulse is transmitted to the line 80. When, however, the insulating segment 70 comes over brush 67 and lifts it out of contact with slip ring 65, relay magnet 70 is energized, armature 72 is swung over to contact 74, with the result that the current in the line is reversed, or, in popular language, 75 a negative impulse is transmitted from main 76 and wire 77. It will therefore be seen that so long as the commutator is operating, current impulses of alternating polarity will be transmitted. 80

Referring still to Fig. 5, it will be observed that the clutch relay 57 is in series with the wiper 54, but that the sunflower segments are connected to the respective lower contacts (as 47, 48, 49, 50) of the keyboard; hence the clutch is not energized, and the commutator and wiper continue to revolve, causing alternating impulses to be transmitted, as long as no key is depressed. On the other hand, when a key is depressed the clutch relay circuit is 90 closed as soon as the wiper reaches the segment which is connected with the depressed key, whereupon the clutch relay is energized and closes the clutch circuit from main 59 through wire 82, armature 83 and wire 84 to ground G'. The commutator and wiper are thus arrested, and the last impulse transmitted, whether positive or negative, is prolonged until the depressed key is released and breaks the clutch relay circuit, thereby permitting 95 the commutator and wiper to start again. It will be understood, of course, that the ticker escapement and type wheel are constructed to operate in harmony with the wiper and commutator, so that the impulses sent over the 100 line as the keys are successively depressed will rotate the type wheel in unison and bring the corresponding type to the printing point. 105

Referring again to Fig. 5, the transmission line 80 is connected to the contacts 86, 87 of 110 the relays 58, 61, and the armatures of these relays are connected to a resistance 88. The latter is connected (by wire 80^a, part of the transmission line) through a printing relay 89 to the escapement magnets 13 of the ticker, 115 which magnets are connected through the shift relay 90 to the "third wire" 91. Across the resistance 88 is a shunt through the armature 92 of relay 60, so that when the relay is energized the resistance is shunted out, 120 thereby allowing strong current to flow over the line, as will be readily understood.

The operation of the system illustrated in Fig. 5 will now be readily understood. Suppose for example that a key in the outer keyboard bus 41 is depressed. As soon as the wiper 54 reaches the sunflower segment which is connected with the depressed key current flows from main 59 through wire 94, relay 58, wire 95, bus 41, the depressed key and the sun- 130

flower segment connected therewith, wiper 54, brush 56, wire 95 and relay magnet 57 to ground G. This energizes the clutch 69 and stops the commutator as already described, and also energizes relay 58, which draws its armature away from contact 86; but before these operations take place the alternating impulses sent by the transmitting pole-changer 70-71-72 flowed from and to the armature 72 through line wire 80 (including the repeat key 95), contact 87, armature of relay 61, wire 96, resistance 88, line wire 80^a, press relay 89, escapement magnets 13, wire 97, shift relay 90 and wire 98 to the grounded third wire 91^a. Because of the resistance 88 the line current is relatively weak. The ticker shift-relay 90 is quick-acting on strong current but is so designed (including the tension of spring 99 which urges its armature 100 away from contact 101) that the field produced by the weak current flowing when the final transmitted impulse is prolonged by the arrest of the commutator is not strong enough to swing the armature 100 into engagement with contact 101, and consequently the shift magnet is not energized since its circuit remains open at contact 101. The prolonged weak current does, however, give the press relay 89 a field strong enough to actuate its armature 102, whereupon local current flows from main 59^a through wire 103, contact 104, armature 102, press magnet 16, and wires 105, 106 to the third wire 91^a. The press magnet is thus energized and the ticker platen is actuated, making an imprint from the selected type on the type wheel now corresponding to the outer keyboard bus 41. Now suppose that the operator depresses a key in the inner group, associated with the inner bus 42 and with the other row of type on the ticker type wheel, and then releases the key that had been depressed in the outer group. As soon as the latter key rises the circuit previously traced through the sunflower is broken, the clutch is deenergized, and the wiper and commutator start, sending alternating impulses over the line as before until the wiper reaches the sunflower segment which is in series with the depressed inner key. Current now flows from main 59^a, wire 107, relay 61, wire 108, transmitter shift-relay 60, wire 109, inner bus 42, and thence through the sunflower and clutch relay 57, causing the commutator to be arrested. Relay 60 being thus energized a shunt, composed of wire 110, armature 111, contact 112 and wire 113, is laid across resistance 88, and consequently the current sent over the line, including the prolonged final impulse, is strong, with the result that the field of the ticker shift-relay 90 is strong enough to close the local shift circuit from main 59^a, wire 114, armature 100, contact 101, shift magnet 32, and wire 106 to third wire 91^a. Magnet 32 being thus energized the shift mechanism is actuated, and when the press magnet acts the imprint is

made from the type row corresponding to the inner group of keys at the keyboard.

To repeat a character it is only necessary to keep the depressed key down and depress and release spring-actuated repeat key 95, 70 which is conveniently located on or near the keyboard. This opens the line circuit (without, however, causing any movement of the ticker type wheel since the clutch relay 57 remains energized), permitting the press magnet 16 to be de-energized and re-energized, causing a second imprint. If a strong current were flowing, opening the line de-energizes the shift relay 90, but when the line is closed again by release of the repeat key the 80 relay named is re-energized and the shift mechanism is thereby restored to the condition existing just before the line was opened.

As previously stated, the press magnet 16 and shift-magnet 32 can be in series with the 85 escapement magnets 13, omitting the relays 89, 90. This arrangement is illustrated in Fig. 6. In this figure line wire 80^a goes to the press magnet, which is connected to the escapement magnets, and the latter are connected to the shift magnet. The relay system of control is preferred, however, as being less critical in design and adjustment, and affording positive actuation of the printing and shift mechanisms by reason of the greater 90 amount of current available in the local circuits.

It will be noted that when a key in the outer ring of the keyboard (Fig. 5) is depressed, relay 58 is energized and its armature drawn off contact 86 but that the line circuit is not broken, since it is still closed by way of contact 87 and the armature of relay 61, the two armatures being connected together and the two contacts being connected together. Similarly, when a key in the inner ring is depressed relay 61 is energized and its armature swung off contact 87, but the line circuit is still complete through contact 86. It might therefore be supposed that these relays have 105 no useful function, but in fact they are highly advantageous, as will now be explained. Assume that the relays are omitted, wire 80 being connected directly to wire 110 and resistance 88, and wires 107, 108 being connected; 110 and that it is desired to print the character corresponding to outer key 45, followed by the character of the adjacent inner key 43. In other words a character in one row of the ticker type wheel is to be followed by the immediately adjacent character in the other row. In such case the obvious procedure would be for the operator to depress key 45, then as soon as the imprint is made, depress key 43 and at once release key 45. But such operation would not open the line circuit and thereby cause lowering of the platen and spacing of the tape for the next imprint, since a new circuit through the sunflower and clutch relay was established by the depression 115 120 125 130

of key 43. Hence no imprint would be made for key 43, and it would therefore seem necessary to release key 45 before depressing key 43. But release of key 45 before the other is depressed would break the sunflower circuit, and the commutator would at once start and make a complete revolution, stopping only when the wiper 54 reached segment 52 again, thus occasioning a loss of time. It is therefore necessary to proceed as follows: depress key 45, depress the repeat key 95 (thereby opening the line without affecting the sunflower and commutator), depress key 43, release key 45, and then release the repeat key.

On the other hand, with the relays 58-61 in the system, as shown in Fig. 5, depression of key 45 energizes relay 58 and swings its armature off contact 86 as already described, and depression of key 43 while 45 is held down energizes relay 61, which withdraws its armature from contact 87, thereby opening the line circuit 80, and causing ticker relay 89 to be energized, which by opening the local circuit of the press magnet 16 drops the platen and spaces the tape. Then when key 45 is released, the consequent de-energization of relay 58 closes the line circuit at contact 86, relay 90 closes the local shift-circuit, relay 89 closes the local printing circuit, and the imprint is made. It will therefore be seen that with the relays 58, 61 in the system the operator can "step across" directly, from one type row to the other in either direction, without using the repeat key or otherwise varying the normal method of operation.

The keyboard 40 is preferably constructed as shown, in detail, in our copending application Serial No. 126,774, filed August 3, 1926. In general the keyboard, sunflower, commutator, clutch, clutch-relay 57, line relays 58, 61, shift-relay 60, resistance 88, repeat key 95, and pole-changing relay 70-71 are located at the transmitting station, while press-relay 89, shift-relay 90 and shift magnet 32 are located at the receiving station.

In the construction shown in Fig. 7 the shift is effected by the shift magnets independently of the printing movement of the platen. For this purpose the shift 24^a, rocked in one direction by the magnets 32^a and in the other by the spring 33^a, has a vertical slot 120 in its upper end, into which projects a finger 121 extending forwardly from the upper arm of the shift lever 21. It will therefore be seen that when the magnets 32^a let go and permit the spring 33^a to swing the shift arm clockwise the lever 21 will be rocked in the same direction, with corresponding movement of the pivoted platen so that the next imprint will be made from type wheel 10. Similarly, when the arm is rocked by the magnets the reverse action takes place and the imprint will be made from type wheel 11, as in Fig. 7.

It is to be understood that the invention

is not limited to the specific construction herein illustrated and described but can be embodied in other forms without departure from its spirit.

We claim—

1. In a printing telegraph receiver adapted for operation on a single transmission circuit, in combination, printing elements comprising a plurality of type wheels and a platen for making imprints therefrom, means actuated by the imprint-making operation and movement of the platen for producing relative shifting movement of the printing elements to cause the imprint to be made from one or another of the type wheels, and controlling means for the shifting means, dependent for operation upon change of current strength over the single transmission circuit. 70

2. In a printing telegraph receiver, in combination, a single transmission circuit, relatively movable printing elements comprising a plurality of type wheels and a platen for taking imprints therefrom, means for producing such relative movement of the printing elements, mechanism actuated by said means to produce relative shifting movement of the printing elements to cause the imprint to be made from one or another of the type wheels singly, and controlling 90 means for the shifting mechanism, dependent for operation upon change of current strength over the single transmission circuit.

3. In a printing telegraph receiver, in combination, a single transmission circuit, a plurality of type wheels and means controlled by current over said circuit to set the type wheels, a platen cooperating with the type wheels, means for actuating the platen, means actuated by movement of the platen itself 105 for shifting the platen relatively to the type wheels to take imprints from one type wheel or another, and controlling means for said platen shifting means, dependent for operation upon change of current strength over 110 the single transmission circuit.

4. In a printing telegraph receiver, in combination, a single transmission circuit, a plurality of type wheels and means controlled by current over said circuit to set the 115 type wheels, a platen cooperating with the type wheels, platen-actuating means, means actuated by the movement of the platen itself for shifting the platen from one type wheel to another; and means, including an electromagnet dependent for energization upon change of current strength over the single transmission circuit, for controlling the platen shifting means. 120

5. In a printing telegraph receiver, in 125 combination, a single transmission circuit, a plurality of type wheels and means controlled by current over said circuit to set the type wheels, a platen cooperating with the type wheels, platen-actuating means, mechanism 130

- actuated by the movement of the platen for shifting the platen from one type wheel to another, controlling means for the shift mechanism, an electromagnet for actuating the controlling means, a local circuit for the electromagnet, and a relay in said single transmission circuit to control the local circuit, the relay itself being energized only by strong current over the single transmission circuit.
6. In a printing telegraph receiver, in combination, a single transmission circuit, a plurality of type wheels and means controlled by current over said circuit to set the type wheels, a platen cooperating with the type wheels, platen-actuating means, means actuated by the movement of the platen for shifting the platen from one type wheel to another, a member adapted when actuated to determine the type wheel to which the platen will be shifted, and electromagnetic means for actuating said member, dependent for operation upon change of current strength over the single transmission circuit.
7. In a printing telegraph receiver, in combination, a plurality of type wheels, a platen cooperating therewith, platen-actuating means, means for shifting the platen from one type wheel to another, actuated by movement of the platen itself, a pivoted shift-control arm cooperating with the platen shifting means to determine the type wheel to which the platen will be shifted, a transmission circuit, and an electromagnet for actuating the shift-control arm, dependent for energization upon change of current strength over said transmission circuit.
8. In a printing telegraph receiver, in combination, a plurality of type wheels, a platen cooperating therewith and shiftable from one to another, platen-actuating means, platen-shifting means including a member movable in different directions to shift the platen, shiftable actuating fingers to move said member when the platen is actuated to make an imprint, and electromagnetic means for shifting said fingers.
9. In a printing telegraph receiver, in combination, a plurality of type wheels, a platen cooperating therewith and shiftable from one to another, platen-actuating means, platen-shifting means including a member movable in different directions to shift the platen, shift selecting means comprising an arm shiftable to a plurality of positions relative to said member, fingers carried by the arm to shift the member in one direction or another according to the position of the arm, and an electromagnet for shifting the arm.
10. In a printing telegraph receiver, in combination, a plurality of type wheels, a platen cooperating with the type wheels, a platen-actuating arm on which the platen is shiftable from one type wheel to another, a lever associated with the platen to shift the same on said arm, a shifting-control member shiftable to a plurality of positions relative to said lever to variably actuate the same for shifting movement according to the position of said member when the platen is moved toward the type wheels by said arm, and an electromagnet for shifting the said member.
11. In a printing telegraph receiver, in combination, a plurality of type wheels, a platen movable toward and from the type wheels to take imprints therefrom; means for shifting the platen from one type wheel to another, comprising a lever connected with the platen, a shift-arm movable relatively to the lever, and a plurality of fingers carried by the arm to rock the lever variably when the platen is moved toward the type wheels to take an imprint; and electromagnetic means for positioning the shift-arm.
12. In a printing telegraph receiver, in combination, a pair of type wheels rotatable to bring to the impression point characters in pairs, one on each wheel, a forked platen, a platen-actuating arm on which the platen is pivoted whereby the platen can be rocked to cooperate with either type wheel singly, a lever carried by the platen-actuating arm and connected with the platen to rock the same, a shift-control arm adapted to swing transversely of said lever and having means adapted to cooperate with the lever to rock the same in one direction or the other according to the position of the arm when the platen is actuated to make an imprint, a transmission circuit, and electromagnetic mechanism for actuating said arm according to the strength of current in said transmission circuit.
13. In a printing telegraph receiver, in combination, a pair of type wheels rotatable on a common axis to bring pairs of characters, one on each wheel, to the printing position simultaneously, a platen shiftable to cooperate with the type wheels singly, a lever associated with the platen to cause shifting movement thereof by and from the platen movement and when the platen is actuated to print a character, a shift arm extending across the lever and having means to cooperate with the lever to rock the same when the platen is actuated, according to the position of the arm relative to the lever, an electromagnet having an armature connected with the shift-arm to move the same in one direction, and a spring for moving the shift-arm in the opposite direction.
14. In a printing telegraph receiver, in combination, a pair of type wheels, a platen movable upwardly to cooperate therewith, a platen-actuating member on which the platen is shiftably mounted whereby to cooperate with the type wheels singly, a lever mounted on the platen-actuating member to shift the platen when the latter is moved upwardly, an arm overhanging the lever, shiftable transversely thereof and having fingers to engage

one arm or the other of the lever and rock the latter in opposite directions according to the position of said arm relative to the lever, and means for shifting said arm relatively to the lever, comprising electromagnetic mechanism adapted to be controlled by current over a transmission circuit.

15. In a printing telegraph receiver, in combination, a pair of type wheels, a platen movable upwardly to cooperate therewith, a platen-actuating member on which the platen is shiftably mounted whereby to cooperate with the type wheels singly, a lever mounted on the platen-actuating member to shift the platen when the latter is moved upwardly, an arm overhanging the lever, shiftable transversely thereof and having fingers to engage one arm or the other of the lever and rock the latter in opposite directions according to the position of said arm relative to the lever, and means for shifting said arm relatively to the lever, comprising an electromagnet having an armature connected with the said arm to shift the same in one direction when the magnet is energized, a spring to shift the arm in the other direction when the magnet is deenergized, a local circuit for the magnet, and a relay to control the local circuit, said relay being adapted to be included in a transmission circuit.

16. In a printing telegraph receiver, in combination, a plurality of type wheels rotatable on a horizontal axis to bring a plurality of characters to the printing position simultaneously, a platen-actuating arm pivoted in rear of the type wheels and extending forwardly below the same, a platen mounted on the arm below the type wheels and shiftable on the arm to cooperate with one type wheel or another singly, a platen-shifting member connected with the platen and adapted when actuated to shift the platen when the platen-actuating arm is swung up

to make an imprint, and actuating means for the platen-shifting member, comprising an electromagnet below the type wheels and platen, an armature for the electromagnet, and an arm connected with the armature for actuation thereby, said arm extending upwardly adjacent to the platen-shifting member and having means to cooperate variably therewith according to the position of said arm relative to the shifting member.

17. A printing telegraph receiver as set forth in claim 16, in combination with a transmission circuit to control the rotation of the type wheels and the operation of the platen-actuating member, a local circuit for the electromagnet, and a relay in said transmission circuit to control the local circuit according to the strength of the current in said circuit.

18. In a printing telegraph receiver adapted for operation on a single transmission circuit, in combination, printing elements comprising a plurality of type wheels and a platen for making imprints therefrom, means for producing a relative approaching movement of the printing elements to cause the platen to take an imprint from the wheels, means for relatively laterally shifting the platen with respect to the wheels to permit the platen to imprint from one or the other of the wheels, means for selectively controlling the aforesaid lateral shifting action, said means comprising means dependent for operation upon a change of current strength over the single transmission circuit, and means for producing actual lateral shifting movements as selected by the aforesaid means by and upon the relative imprinting movement of the printing elements.

In testimony whereof we hereto affix our signatures.

GEORGE S. HILTZ.
